UNITED STATES PATENT OFFICE.

HUBERT DALTON, OF NEW YORK, N. Y.

DESIGN FOR A SUPPORTING BASE AND BRACKET.

45,857.

Specification for Design.

Patented June 2, 1914.

Application filed April 1, 1914. Serial No. 828,915. Term of patent 7 years.

To all whom it may concern:

Be it known that I, HUBERT DALTON, a citizen of the United States of America, residing at 498 West End avenue, in the city of New York, county of New York, and State of New York, have invented a new, original, and ornamental Design for a Supporting Base and Bracket, of which the following is a specification, reference being had to the accompanying drawing, forming a part thereof.

The figures of the drawing, of which

Figure 1 may be termed a rear elevation, and Fig. 2 may be termed a side elevation looking toward the left of Fig. 1, disclose a supporting base and bracket showing my new and ornamental design.

I claim:

The ornamental design for supporting base and bracket, as shown.

HUBERT DALTON.
